(57) **CLAIM**

The ornamental design for a dog chew toy, as shown and described.

DESCRIPTION

FIG. 1 is a top front perspective view of a dog chew toy, showing my new design;

FIG. 2 is a front elevation view thereof, with the rear elevation view being a mirror image thereof;

FIG. 3 is a right side elevation view thereof, with the left side elevation view being a mirror image thereof;

FIG. 4 is a top elevation view thereof; and,

FIG. 5 is a bottom elevation view thereof.
